United States Patent Office

Des. 192,104
Patented Jan. 16, 1962

192,104

READING PROJECTOR

Glen W. Offensend and Norman J. Rosenburgh, Rochester, N.Y., assignors to Eastman Kodak Company, Rochester, N.Y., a corporation of New Jersey

Filed Mar. 10, 1961, Ser. No. 64,209

Term of patent 14 years

(Cl. D61—1)

Fig. 1

Fig.2

Fig.3

FIG. 1 is a front perspective view of a reading projector showing our new design;

FIG. 2 is a rear perspective view thereof;

FIG. 3 is a top perspective view thereof.

The dominant features of our new design are shown in solid lines in the drawings.

We claim:

The ornamental design for a reading projector, as shown and described.
